TEMPLET FOR STAIRWAYS

Darwin K. Pelz, Blairstown, Iowa, assignor to Hydrodynamic Development Corporation, Inc., Baltimore, Md., a corporation of Maryland

Filed July 29, 1966, Ser. No. 3,268

Term of patent 14 years

(Cl. D52—6)

FIG. 1 is a perspective front view of a templet for stairways showing my new design with the back side being of like appearance,

FIG. 2 is an end view thereof,

FIG. 3 is a top view thereof,

FIG. 4 is a bottom view thereof, and

FIG. 5 is a perspective front view similar to FIG. 1 but showing a slight modification thereof along the bottom edge.

I claim:

The ornamental design for a templet for stairways, as shown and described.
